SPINNING RING AND TRAVELER THEREFOR

Henry C. Herr, Buffalo, N. Y., assignor to Herr
Manufacturing Company, Inc., Buffalo, N. Y., a
corporation of New York

Application January 9, 1932, Serial No. 535,747

21 Claims. (Cl. 118—59)

This invention relates to certain new and useful improvements in the spinning rings and bar travelers employed in connection with spinning machines.

5 One of its chief objects is to so design and construct the bar traveler and its spinning or bearing ring as to insure a true and uniform action of the traveler and at the same time reduce to a minimum the possibility of the traveler bar 10 being displaced from its operative position.

Another object of the invention is the provision of a bar traveler which is constructed to provide a bearing point at its outer or free ends, thereby bringing its point of wear where breakage of the bar is prevented and insuring its longer life.

A further object is to so construct the spinning ring and bar-traveler that an efficient and effective bearing contact between these parts is provided which affords a more stable and non-whipping action of the traveler, permitting its reliable operation at high speeds, and which affords a material reduction in the tension on the threads and accordingly reducing to a minimum the 25 tendency of the thread to break or be otherwise injured.

A still further object is to provide a device of this character which is simple in construction, efficient and reliable in operation, and wherein 30 the traveler bar is designed to readily fit different sized spinning rings.

In the accompanying drawing:—

Figure 1 is a top plan view of a spinning ring and bar traveler embodying my invention. Figure 2 is a cross section thereof taken on line 2—2, Figure 1. Figure 3 is an enlarged fragmentary cross section taken on line 3—3, Figure 1. Figure 4 is an enlarged fragmentary sectional plan view showing the manner in which 40 the traveler arms bear against the ring. Figure 5 is a perspective view of the bar traveler. Figure 6 is a perspective view of the slightly modified form of the bar traveler.

Similar characters of reference indicate corresponding parts throughout the several views.

In spinning machines of the character to which my invention is particularly applicable, the threads to be twisted are delivered by feed rolls (not shown) to a take-up spool or bobbin 10 50 mounted on a revolving spindle and traversing the same in a vertically reciprocating bar 11, the spool extending through an opening 12 in the bar, as seen by dotted lines in Figure 2.

Mounted on the reciprocating bar 11 and surrounding the take-up spool 10 is the supporting

base or holder for the spinning or traverse ring upon which the traveler, indicated generally by the numeral 13, is adapted to revolve. During the operation of the spinning machine, the bar traveler assumes a more or less upright or outwardly directed position and revolves with and about the take-up spool, the thread passing under the traveler before being wound upon the spool and the traverse bar being reciprocated so that the threads are uniformly wound in layers upon 60 the spool.

The holder which supports the ring is preferably stamped or formed from sheet metal and consists of an annular attaching base 14 having a central opening 15 therein through which the 70 spool 10 extends, and at its outer edge it is provided with a pair of oppositely facing slotted ears 16 for securely fastening the base to the bar. Rising from the outer edge of this base are yieldable clamping posts or brackets 17 for detachably 75 receiving and holding the spinning ring in place on the holder. The inner edge of the holder-base is provided with an upwardly-facing annular flange or neck 18 which preferably terminates at its upper edge in an outwardly-flaring 80 rim or extension 19.

In its preferred form the spinning ring for guiding the bar traveler about the take-up spool consists of a self-contained track and lubrication unit adapted to be mounted on the holder in 85 frictional engagement with its yielding brackets 17 and is composed of a lower or base-section 20 and an upper or cap-section 21, these sections being fastened as a unit to form a lubricant chamber or reservoir 22. At their outer edges 90 the sections 20 and 21 are provided with depending rims or flanges 23 and 24, respectively, which are nested one within the other and jointed by a pressed fit, the base-section flange 23 preferably extending below the flange of the companion section and resting edgewise on the top side of the holder-base 14. The outer face of the cap-section flange 24 is adapted to firmly engage the yieldable brackets 17 to firmly hold 95 the ring in position on the holder. The inner edge of the base-section 20 of the ring is convexly curved, as indicated at 25, to form a supplementary bearing for the traveler, while the inner peripheral face of its flange 23 is preferably arcuate or concave in cross section, as indicated at 26, the proper curvature being preferably determined from a radius whose center is positioned substantially tangentially of the curved bearing edge 25, this concave face constituting the main bearing for the bar traveler. 100 105 110

In its top side the cap-section 21 is provided with a filling opening 27 through which the lubricant is introduced into the chamber 22 of the ring.

The bar traveler 13 is constructed of steel wire 5 and preferably shaped in the manner shown clearly in Figures 3, 4 and 5, the same being bent into substantially U-shape to form a thread-engaging or guide bar 28, legs 29 depending from the ends of the bar and arranged to extend freely 10 into the annular space or channel 30 formed between the neck 18 of the holder-base 14 and the inner or supplementary bearing edge 25 of the spinning ring, and extensions or bearing arms 31 projecting outwardly from the lower ends of 15 the legs and adapted to enter the lateral continuation of the channel into more or less hook-like engagement with the ring, in the manner shown in Figures 3 and 4. These bearing arms are directed outwardly and upwardly at a slight 20 angle to the horizontal and are likewise deflected or bent laterally toward each other at substantially an obtuse angle to the vertical or to a common vertical plane passing through the legs 29 of the bar, as clearly shown in Figures 1 25 and 4. Short of their free ends, the arms 31 are provided with convex bearing portions 32 which, under certain conditions, are adapted to contact at their upper sides with the underside of the base section 20 of the spinning ring. In 30 the normal operative position of the bar traveler, the free ends of the arms 31 are adapted to abut against the bearing face 26 of the spinning ring, such face being highly finished or polished and the arm-ends riding over this face in a wiping-like manner. During such normal operation, the 35 legs 29 of the traveler run clear of and out of contact with the supplementary bearing face 25 of the ring. Should there be a sudden upward movement of the traveler relatively to the ring, as when the tension of the thread draws up suddenly, then the convex bearing faces 32 of the traveler-arms 31 will contact with the underside of the base-section 20 of the ring. As the end bearing portions of the traveler arms wear, the 40 clearance between the legs 29 and the supplementary bearing face 25 of the ring is gradually lessened and eventually the legs make contact with and bear against such bearing faces 25, at which time the traveler will have a two point 45 bearing with the ring, one at the main bearing face 26 with the ends of the arm, and the other at the supplementary bearing face 25 with the legs of the traveler.

While the cross or guide bar 28 of the traveler 50 may be straight, as shown in Fig. 6, it is preferably shaped in the manner shown in Figures 4 and 5, the same being bent or deflected inwardly from its opposite ends into substantially the form of a V, which arrangement effectually prevents 55 the thread from working to the corners of the traveler and allows it to traverse the bar between the end thereof and the high point of its bend, thereby preventing the thread traveling over a fixed point and wearing a cut or groove in the 60 cross bar of the traveler, and avoiding the liability of damaging or breaking the thread.

For the purpose of placing the bearing face 26 of the ring in communication with its lubricant chamber 22, the base-section 20 of the ring is 65 provided in its underside and preferably at the junction or corner between the flange 23 and bottom side of the base-section with an annular groove or channel 33 which is in communication with the lubricant chamber through one or more 70 ports 34. By this construction the lubricant is 75

delivered onto the bearing face 26 and also to the adjoining underside of the base-section of the ring.

I claim as my invention:—

1. A device of the character described, comprising a spinning ring having a peripheral internal bearing element facing the ring-axis, and a bar traveler mounted on said ring including a substantially straight cross bar adapted to subtend an arc of the inner edge of the ring and having depending legs at its ends terminating in outwardly-facing bearing arms disposed at an angle to the common plane intersecting said legs and in opposing endwise relation to the bearing element, the free ends of said arms being arranged to abut endwise against said bearing element. 80

2. A device of the character described, comprising a spinning ring having a peripheral internal bearing element, and a bar traveler mounted on said ring and having depending legs terminating in outwardly-facing bearing arms engageable at their terminal edges with said bearing element, said arms being deflected laterally and outwardly at an obtuse angle to the common plane intersecting their legs and toward each other. 85

3. A device of the character described, comprising a spinning ring having inner and outer concentric bearing elements, and a bar traveler mounted on said ring and having depending legs terminating in outwardly-facing bearing arms, 90 the free ends of said arms abutting against said outer bearing element and said legs being normally spaced from the inner bearing element. 95

4. A device of the character described, comprising a spinning ring having inner and outer concentric bearing elements, and a bar traveler mounted on said ring and having depending legs disposed normally in spaced relation to said inner bearing element and terminating at their lower ends in outwardly-facing bearing arms disposed obliquely to the plane of said legs, the free ends of said arms being arranged to abut against 110 said outer bearing element. 115

5. A device of the character described, comprising a spinning ring having a bearing surface 120 on its underside and a peripheral bearing surface adjoining the same, and a bar traveler mounted on said ring and having outwardly-facing bearing arms deflected laterally from the plane of the bar and toward each other and engageable at their 125 free ends with said peripheral bearing surface, said arms terminating short of their free ends in convex bearing portions engageable with the under bearing surface of the ring.

6. A device of the character described, comprising a spinning ring having a lubricant reservoir therein and a bearing surface on its underside and a peripheral bearing surface adjoining the same, said reservoir having a discharge port for directing the lubricant at a point between said bearing 135 surfaces, and a bar traveler mounted on said ring and having outwardly-facing bearing arms engageable at their free ends with said peripheral bearing surface and short of such free ends with the under bearing surface of the ring. 140

7. A device of the character described, comprising a holder consisting of a flat base member containing a central opening through which a take-up spool is adapted to extend, an annular upstanding flange extending about said opening, a spinning ring mounted on said base member in spaced concentric relation to its flange and having a peripheral internal bearing element, and a bar traveler mounted on said ring and having depending legs arranged to enter the annular space 150

5 between the ring and said base member flange and terminating in outwardly-facing bearing arms engageable at their free ends with said bearing element, said arms being deflected out of the plane of their legs and toward each other.

8. A device of the character described, comprising a spinning ring having an internal peripheral bearing face curved in a direction at right angles to its circumference, and a bar traveler mounted on said ring for engagement at its ends with said curved bearing face.

15 9. A device of the character described, comprising a spinning ring for a bar traveler having outwardly-facing bearing arms, said ring having an annular flange extending around the periphery thereof below its underside and constituting a bearing face for the ends of the traveler bearing arms, said bearing face being concave in cross section.

20 10. A device of the character described, comprising a hollow spinning ring for a bar traveler adapted to contain a supply of lubricant, said traveler having outwardly-facing bearing arms, and an annular flange extending around the periphery of said ring below its underside and constituting a bearing face for the ends of the traveler-arms, said ring having a downwardly-facing groove at the junction of its underside and the ring-flange and also having ports for establishing communication between said groove and the interior of the ring.

25 11. A device of the character described, comprising a ring holder containing a neck through which a take-up spool is adapted to extend, a spinning ring for a bar traveler having outwardly-facing bearing arms mounted on said holder in concentric spaced relation about its neck to provide an annular channel between the inner and outer peripheral faces of said ring and said hollow-neck for the passage of the traveler, said ring having a flange depending from its periphery below its underside and constituting a bearing against which the ends of the bar traveler arms are adapted to abut, said flange resting at its lower edge on the top side of the holder.

30 12. A bar traveler for spinning machines, comprising a substantially straight cross bar, legs depending from the ends thereof, and bearing arms extending outwardly and laterally from the lower ends of said legs and disposed at an obtuse angle to the cross bar, the terminal edges of said arms constituting bearing elements for the traveler.

35 13. A bar traveler for the rings of spinning machines, having depending legs terminating in outwardly-facing bearing arms deflected laterally toward each other in oblique relation to the plane of the legs, the terminal edges of said arms constituting bearing points engageable with the spinning ring.

40 14. A bar traveler for spinning machines, having depending legs terminating in outwardly-facing bearing arms deflected laterally toward each other in oblique relation to the plane of the

45 legs, the free ends of the arms constituting bearing points and said arms terminating short of their ends in convex bearing portions.

50 15. A bar traveler for spinning machines, having a thread-engaging bar and legs depending from the ends thereof, said bar being deflected laterally from a line connecting said legs, to provide outwardly-diverging, thread-engaging portions for controlling the traverse of the thread along the bar.

55 16. A bar traveler for spinning machines, having a thread-engaging bar and legs depending from the ends thereof, said bar being bent laterally from its ends to a point intermediate its ends, to provide outwardly-diverging thread-engaging portions radiating substantially centrally of the bar.

60 17. A bar traveler for spinning machines, having a thread-engaging bar and legs depending from the ends thereof, said bar being bent laterally into substantially the shape of a V to provide inwardly-converging, thread-engaging portions for controlling the traverse of the thread toward the center of the bar.

65 18. A bar traveler for spinning machines, comprising a cross bar bent laterally intermediate its ends to provide outwardly-diverging, thread-engaging portions radiating substantially centrally of the bar, legs depending from the ends of said bar, and bearing arms extending outwardly from the lower ends of said legs and bent laterally at an obtuse angle to the cross bar.

70 19. A device of the character described, comprising a spinning ring having a peripheral internal bearing element facing the ring-axis, and a bar traveler mounted on said ring to subtend an arcuate portion thereof and having a substantially V-shaped, thread-guiding bar having its apex facing inwardly toward the ring-axis and having bearing arms at the ends of said bar disposed in opposing endwise relation to said bearing element and arranged for simultaneous abutting engagement at its terminal edges with said bearing element.

75 20. A device of the character described, comprising a spinning ring for a bar traveler having depending legs terminating in outwardly-facing bearing arms bent laterally from the ends of said legs and substantially obliquely to the plane intersecting the legs, said ring having an annular flange extending around the outer periphery thereof below its underside and constituting a main bearing face against which the outer ends of said bearing arms are adapted to abut, the inner periphery of said ring constituting a supplementary bearing with which the legs of the traveler are adapted to engage.

80 21. A bar traveler for a spinning ring, comprising a thread-guiding bar adapted to subtend an arc of the inner edge of the ring and having depending legs terminating in outwardly-facing bearing arms disposed at an obtuse angle to the common plane intersecting said legs.
